UNITED STATES PATENT OFFICE

CORA L. BLACK, OF SAN FRANCISCO, CALIFORNIA

DESIGN FOR A DOLL

Application filed December 2, 1930. Serial No. 37,865. Term of patent 3½ years.

To all whom it may concern:

Be it known that I, CORA L. BLACK, a citizen of the United States, residing at the city and county of San Francisco, State of California, have invented a new, original, and ornamental Design for a Doll, of which the following is a specification, reference being had to the accompanying drawings, forming part thereof.

Fig. 1 is a front elevation of the doll.

Fig. 2 is a side elevation of the same.

I claim:

The ornamental design for a doll, substantially as shown.

CORA L. BLACK.
